LIGHT SOURCE FOR RECORDING SOUND
ON FILM AND METHOD OF PRODUCING
SAMEStewart C. Whitman, New York, N. Y., assignor
to Whitman Sound Systems, Ltd., Dover, Del.,
a corporation of Delaware

Application September 19, 1932, Serial No. 633,911

16 Claims. (Cl. 179—100.3)

This invention relates to new and useful improvements in the art of recording sound on film and more particularly to an electronically controlled light source to accomplish these results.

An object of this invention is to provide a photographic device capable of recording sound frequencies throughout and beyond the usual audible range.

Another object of this invention is to provide a sound recording apparatus which can be so accurately controlled as to produce a faithful photographic sound record on film.

A further object of the invention lies in the production of a simple sound recording apparatus which is light in weight and occupies comparatively small space.

Still another object of the invention resides in the elimination of supervision necessitated by the use of complicated mechanical and optical devices in sound recording.

With these and other objects in view, my invention consists in the novel features of construction, combination and arrangement of parts as will be hereinafter referred to and more particularly pointed out in the specification and claims.

In the drawing, forming a part of this application:

30 Figure 1 is a vertical longitudinal section through my device, including a schematic diagram of associated electrical circuits.

Figure 2 is a vertical transverse section taken on line 2—2 of Figure 1.

35 Figure 3 is an elevational view of the forward end of the device.

Figure 4 is a fragmentary horizontal section taken on line 4—4 of Figure 1, and

40 Figure 5 is a vertical transverse section taken on line 5—5 of Figure 1.

The above elements and their various arrangements will be more particularly described in the following disclosure.

At the present time sound recording on film is 45 accomplished by one of two methods: the mechanical light shutter which produces a variable area, record, and the variable density record which is obtained by the optical or mechanical reduction of the light from a variable source to 50 a fine slit. Both of these methods possess inherent drawbacks which limit the sound frequencies which can be successfully recorded. The variable area system is limited because of inertia and the variable density system because of 55 the large light source area.

The present invention presents a method of actually controlling by electronic means the size of the recording light slit and also its brilliancy. Since for practical purposes there is no limit 60 to the possible reduction in slit width when

electronically controlled, it is apparent that such a device would achieve a sound record having both variable area and variable density characteristics and which would include all impressed frequencies.

A cathode-ray oscilloscope tube of special design is utilized. Referring to the drawing in which similar reference characters designate corresponding parts throughout the several views, the numeral 6 designates the glass envelope of a 10 tube constructed according to the present invention. A glass stem 7 is sealed thereto and extends inwardly, terminating in the seal press 8 which carries sealed therein the lead-in wires 9, 10, 11 and 12 and the support wires 13 and 15 14. The lead-in wires 10 and 11 have mounted thereon an electron-emitting cathode preferably in the form of a helically wound tungsten wire as shown at 15. The lead-in wire 12 and the support wire 13 have mounted thereon, and surrounding the cathode 15, a control electrode 16 which is composed of any suitable metal, such as nickel or molybdenum, and has the form of a hollow cylinder. The lead-in wire 9 and the support wire 9a extend beyond the cathode assembly with its control electrode and serve to support the anode 17. The anode 17 has the form of a disc, the diameter of which is substantially equivalent to the inner diameter of the tube envelope 6. This anode may be composed of any suitable material such as nickel. Centrally disposed on the surface of anode 17 and adjacent to the cathode 15 is provided a short cylindrical member 18 which is approximately of the same diameter as the control electrode 16. The free edge of the cylinder 18 is slightly flanged as shown at 19. The anode 17 also is provided at its center with a small rectangular slot 20 of dimensions sufficiently small to be circumscribed by the cylinder 18. The actual dimensions of a slot which operates successfully are .200 inch by .010 inch.

The elements so far described constitute the source of an electron beam of proper shape and strength for the purpose of this invention. This 45 electron beam is obtained as follows: The cathode 15 is connected to the energizing battery through the wires 22 and 23 and is brought to the electron emitting temperature thereby. The stream of electrons is condensed to a small cylindrical beam 50 by means of the surrounding control electrode 16 which is negatively charged by the bias battery 24 and the connecting wire 25. The anode 17 is connected through the wire 26 to the positive high voltage source 27. The strong potential 55 gradient established between the cathode and anode accelerates the electronic stream in the direction of the anode.

The condensed electron stream arrives at the anode at high velocity striking it at the region 60

occupied by the rectangular slot. As a consequence a thin rectangular beam of electrons is projected, still at high velocity, through the anode slot. The beam then traverses the length of the tube passing between two elongated condenser plates or control electrodes 28 and 29, which are arranged along the axis of the tube and parallel to each other. These condenser plates are provided with conductors 31 and 32 which are sealed through the tube at 33 and 34. These conductors are connected across the source of the sound signals, which is shown here as an audio output transformer and is designated by the numeral 35; by the wires shown at 36 and 37. The wires 36 and 37 have connected in series therewith the condensers 38 and 39. The wire 36 also is provided with the variable source of voltage shown at 40. By these means the electron beam travelling between the condenser plates is successively flattened and widened depending on the strength of the instantaneous sound signal voltage. The forward end of the tube is provided with a metal disc 41 which may be cemented in place in any known manner. The disc 41 has mounted thereon a light transparent element which may be a diamond 42 ground in the form of a pyramid as shown in Figures 1 and 3, and preferably of electrically conducting material. The base of this pyramid extends through the disc into the tube and the base surface is substantially normal to the axis of the tube. The base is coated with a suitable luminescent or fluorescent material 43 such as powdered willemite. The stream of electrons after passing through the controlled condenser plates impinges upon this active coating causing it to glow brightly over an area corresponding to that of the wave front of the electronic beam. In appearance this glow takes the form of a brilliant thread of light the thickness of which varies with the strength of the sound signal.

This light is transmitted through the diamond and exposes the film 44 travelling past the outer edge 45 of the diamond. The diamond is used for three reasons. The optical transmission is high. The edge in contact with the film can be accurately ground and polished to form an extremely fine optical slit which will not wear with continued use. Finally, the diamond is electrically conductive so that, if desired, an accelerating voltage may be impressed thereon to increase the velocity of the electron stream. This voltage source is shown dotted at 46 and the connecting wire at 47. If desired, the strength of the electron beam as well as its thickness may be varied. This is accomplished by impressing a portion of the signal voltage from 35 across the cathode 15 and the anode 17. In the drawing this arrangement is shown in dotted lines at 48. The variable source of voltage 40 is used to focus the electronic beam on the desired portion of the active coating 43, so that the maximum amount of light falls on the optical slit at 45.

While I have illustrated above the operation of a tube designed according to my invention, I do not desire to be limited to minor details of construction and circuits but wish to cover broadly the idea of electrically controlling the shape, size and strength of an electronic beam, and thereafter translating the kinetic energy of said beam into radiant light energy for photographic sound recording purposes.

Having thus described my invention what I claim is:

1. In a system for recording sound on film, a cathode ray tube comprising a cathode at one end of said tube, an anode apertured at the point where the stream of cathode rays from said cathode will impinge upon said anode, a pair of control electrodes in said tube on the side of said anode opposite said cathode, the faces of said control electrodes being arranged on opposite sides of the stream of cathode rays passing through the aperture in said anode and substantially parallel with said stream, a fluorescent screen disposed at the end of said tube opposite the end carrying the cathode, said screen being in the path of the stream of cathode rays which have passed through the aperture in said anode and between said control electrodes, and means integrally mounted in said tube for concentrating and directly transmitting without reflection substantially all of the light generated by the impinging of cathode rays on said screen to a point outside said tube and delivering it substantially as a fixed point source of light outside said tube. 5

2. In a system for recording sound on film, a cathode ray tube, a cathode in one end of said tube, a fluorescent screen in the other end of said tube, an anode disposed transversely in said tube adjacent said cathode, said anode being apertured at a point nearest said cathode, a pair of control electrodes disposed in said tube between said anode and said screen, the faces of said electrodes being disposed on opposite sides of the stream of cathode rays issuing from said aperture in said anode and substantially parallel to said stream, means for applying an anode potential between said anode and said cathode, a cylindrical grid electrode surrounding said cathode, means for applying a grid biasing potential between said grid electrode and said cathode of value different than said anode potential and means integrally mounted in said tube for concentrating and directly transmitting without reflection substantially all the light generated by the impinging of cathode rays on said screen to a point outside said tube and delivering it substantially as a fixed point source of light outside said tube. 40 45

3. In a system for recording sound on film, a cathode-ray tube, a cathode in one end of said tube, a pyramidal light transparent element set into the other end of said tube with the base of said pyramidal element inside said tube and disposed transversely of said tube, the base of said pyramidal element being provided with a layer of fluorescent material, the pointed apex of said pyramidal element being outside of said tube, an anode disposed transversely of said tube adjacent said cathode, said anode being centrally apertured at the point thereof nearest said cathode, a pair of control electrodes disposed in said tube between said anode and said pyramidal element, the faces of said control electrodes being on opposite sides of the stream of cathode rays emerging from the aperture in said plate and substantially parallel to said stream, said layer of fluorescent material being disposed in the path of the cathode rays which have passed between said control electrodes, whereby voltage variations impressed on said control electrodes produce corresponding variations in visible light delivered at the external apex of said pyramidal element. 60 65 70

4. In a system for recording sound on film, a cathode-ray tube, a cathode centrally disposed in one end of said tube, a pyramidal light transparent element set into the other end of said tube 75

5 tube substantially at the axis thereof, the base of said pyramidal element being inside said tube substantially perpendicular to the axis thereof, the pointed apex of said pyramidal element being outside said tube, the base of said pyramidal element being provided with a layer of fluorescent material, an anode disposed in said tube substantially normal to the axis thereof and adjacent said cathode, said anode being centrally apertured, a 10 pair of control electrodes disposed in said tube between said anode and said pyramidal element, the faces of said control electrodes being disposed on opposite sides of the axis of said tube and substantially parallel thereto and means for applying anode potential between said anode and said cathode.

15 5. In a system for recording sound on film, a cathode-ray tube, a cathode disposed in one end of said tube, a fluorescent screen disposed in the other end of said tube, an anode disposed transversely in said tube in the proximity of said cathode, said anode being centrally apertured at the point where the normal from said cathode meets said anode, a cylindrical grid electrode surrounding said cathode and structurally and electrically insulated therefrom and having its axis substantially coinciding with the normal from said cathode to said anode, a pair of control electrodes disposed in said tube between said anode and said screen, the faces of said control electrodes being on opposite sides of the stream of cathode rays emerging from the aperture in said anode and being substantially parallel to said stream, means for applying anode potential between said anode and said cathode, means for applying grid biasing potential between said grid electrode and said cathode, and means integrally mounted in said tube for directly transmitting without reflection from said screen visible light directly from said fluorescent screen to a point outside said tube.

20 6. In a system for recording sound on film, a cathode-ray tube, a cathode centrally disposed in one end of said tube, a fluorescent screen disposed in the other end of said tube substantially normal to the axis thereof, a pair of capacity control electrodes disposed one on each side of the axis of said tube and with their faces parallel to said axis, an anode plate disposed in said tube between said cathode and said control electrodes adjacent said cathode substantially perpendicular to the axis of said tube, said anode plate being centrally apertured substantially at the intersection of the axis of said tube with said plate, and a cylindrical control member mounted upon said anode plate on the side thereof adjacent said cathode, said control member being shorter than the diameter of said anode plate and of approximately the same diameter as the corresponding dimension of said cathode and being mounted symmetrically with reference to the axis of said tube, means for applying anode potential between said cathode and said anode, and means for conducting to a point outside said tube the visible light generated by the impingement of cathode rays emitted by said cathode upon said screen.

25 7. In a system for recording sound on film, a cathode-ray tube, a cathode disposed in one end of said tube, a fluorescent screen integrally mounted in the other end of said tube, said screen comprising a light transparent base portion and a fluorescent portion carried by said base portion on the side nearest said cathode, said base portion being electrically conducting, a pair of capacity

control electrodes disposed in said tube, one on each side of the path from said cathode to said screen and substantially parallel to said path, an anode plate disposed transversely in said tube between said cathode and said control electrodes, 5 said anode plate being apertured at the point where the path from said cathode to said screen intersects said anode plate, the base portion of said fluorescent screen being pyramidal with a point projecting outside of said tube and adapted for transmitting visible light from said screen to a point outside said tube, means for applying an anode potential between said anode plate and said cathode, and means for applying a screen accelerating potential between said cathode and 15 the base portion of said screen.

20 8. In a system for recording sound on film, a cathode-ray tube, a cathode disposed in one end of said tube, a pyramidal light transparent element set into the other end of said tube with the apex of said pyramidal element outside said tube and the base of said pyramidal element disposed inside said tube transversely thereof, the base of said pyramidal element being provided with a layer of fluorescent material, said pyramidal element being formed of electrically conducting material, a pair of capacity control electrodes disposed in said tube one on each side of the path from said cathode to said layer of fluorescent material and with their faces substantially parallel to said path, an anode plate disposed in said tube transversely thereof between said cathode and said control electrodes, said anode plate being apertured at the point where the path from said cathode to said layer of fluorescent material intersects said anode plate, means for applying anode potential between said cathode and said anode, and means for applying screen accelerating potential between said cathode and 35 said pyramidal element.

30 40 9. In a system for recording sound on film, a cathode-ray tube, a cathode disposed in one end of said tube, a fluorescent screen disposed in the other end of said tube, said screen comprising a light transparent base portion and a fluorescent portion carried by said base portion on the side nearest said cathode, said base portion being electrically conducting and extending through and outside said tube, a pair of capacity control electrodes disposed in said tube, one on each side of the path from said cathode to said screen and substantially parallel to said path, a cylindrical grid electrode surrounding said cathode, an anode plate disposed transversely in said tube between said cathode and said control electrodes, said anode plate being apertured at the point where the path from said cathode to said screen intersects said anode plate, means for applying an anode potential between said anode plate and said cathode, means for applying grid biasing potential between said grid electrode and said cathode, and means for applying a screen accelerating potential between said cathode and the base portion of said screen.

45 50 55 60 65 70 75 10. In the recording of sound modulated electrical currents on film employing a cathode-ray tube having a cathode, a grid electrode surrounding said cathode and a fluorescent screen comprising an electrically conducting base portion inset in said tube, the method of causing photographic impressions on said film corresponding to said modulated currents which consists in directing a beam of cathode rays from said cathode upon said screen, modulating said beam in accordance with said currents, applying

- 5 a bias voltage between said grid electrode and
said cathode, applying an accelerating voltage be-
tween the base portion of said screen and said
cathode, and concentrating and directly trans-
mitting the visible light formed on said screen
as a modulated fixed point source of light outside
of said tube.
- 10 11. In the recording of sound on film employ-
ing a cathode-ray tube having a cathode, an
anode, a grid electrode surrounding said cathode,
capacity control electrodes and a fluorescent
screen comprising an electrically conducting base
portion inset in said tube, the method of causing
photographic impressions on said film corre-
sponding to audio-frequency variations in an ap-
plied voltage wave, which consists in directing a
beam of cathode rays from said cathode upon
said fluorescent screen, modulating said beam
of cathode rays by applying said voltage wave
between said capacity control electrodes, apply-
ing a screen accelerating potential between said
screen and said cathode and applying a grid
bias potential between said grid electrode and
said cathode for controlling the path of said
beam, converting the energy of said beam of
cathode rays into light of the visible spectrum
by means of said fluorescent screen, and concen-
trating and directly transmitting the light gen-
erated by said fluorescent screen to constitute a
modulated fixed point source of light outside of
said tube.
- 15 12. In a system for recording sound on film, a
cathode ray tube comprising a cathode at one end
of said tube, an anode apertured at the point
where the stream of cathode rays from said
cathode would impinge upon said anode, a pair
of control electrodes in said tube on the side of
said anode opposite said cathode, the faces of
said control electrodes being arranged on oppo-
site sides of the stream of cathode rays passing
through the aperture in said anode and sub-
stantially parallel with said stream, a metal plate
mounted in the end of said tube opposite the
end carrying the cathode, a light-transparent
40 electrically conductive element mounted to pro-
ject through said plate and having a face inside
said tube covered with fluorescent material and
positioned in the path of said stream of cathode
rays, said element terminating in a point ex-
terior of said tube, and means for applying a
positive accelerating potential between said ele-
ment and said cathode.
- 45 13. In a system for recording sound on film, a
cathode-ray tube, a cathode centrally disposed
in one end of said tube, a fluorescent screen
disposed in the other end of said tube sub-
stantially normal to the axis thereof, a pair
50 of capacity control electrodes disposed one
on each side of the axis of said tube and with
their faces parallel to said axis, an anode plate
disposed in said tube between said cathode and
said control electrodes adjacent said cathode sub-
stantially perpendicular to the axis of said tube,
said anode plate being centrally apertured sub-
stantially at the intersection of the axis of said
tube with said plate, and a cylindrical control
60 member mounted upon said anode plate on the
side thereof adjacent said cathode, said control
member being shorter than the diameter of said
anode plate and of approximately the same di-
ameter as the corresponding dimension of said
cathode and being mounted symmetrically with
reference to the axis of said tube, and terminat-
ing in an outwardly flared portion pointing in
the direction of said cathode, means for applying
anode potential between said cathode and said
anode, and means for conducting to a point out-
side said tube the visible light generated by the
impingement of cathode rays emitted by said
cathode upon said screen.
- 65 14. In the recording of sound modulated elec-
trical currents on film employing a fluorescent
cathode ray tube, the method of causing photo-
graphic impressions on said film corresponding
to said modulated currents which consists in
directing the beam of cathode rays from its
source in said tube upon the screen of said tube,
modulating said beam in accordance with said
currents, controlling said beam of cathode rays
by applying perpendicularly to the immediate ini-
tial portion thereof at its source an electrostatic
field, and concentrating and directly transmit-
ting without reflection the visible light formed
20 on the screen of said tube as a modulated fixed
point source of light outside of said tube.
- 70 15. In a system for recording sound on film,
a cathode ray tube, a helical filament cathode
element mounted at one end of said tube co-
axially therewith, a fluorescent screen in the
other end of said tube, an anode disposed trans-
versely in said tube adjacent said cathode ele-
ment, said anode being apertured at a point near-
est said cathode element, a pair of control elec-
trodes disposed in said tube between said anode
and said screen, the faces of said electrodes being
disposed on opposite sides of the stream of
cathode rays issuing from said aperture in said
anode and substantially parallel to said stream,
means for applying an anode potential between
said anode and said cathode element, a cylindri-
cal grid electrode element surrounding said heli-
cal filament cathode element over practically its
entire length and mounted coaxially therewith,
and means integrally mounted in said tube for
concentrating and directly transmitting without
reflection substantially all of the light generated
by the impinging of cathode rays on said screen
to a point outside said tube and delivering it sub-
stantially as a fixed point source of light outside
said tube.
- 75 16. In a system for recording sound on film, a
cathode-ray tube, a helical filament cathode dis-
posed in one end of said tube substantially co-
axially therewith, a fluorescent screen disposed
in the other end of said tube, an anode disposed
transversely in said tube in the proximity of said
cathode, said anode being centrally apertured at
the point where the normal from said cathode
meets said anode, a cylindrical grid electrode
surrounding said helical cathode over practically
its entire length and mounted coaxially there-
with, a pair of control electrodes disposed in said
tube between said anode and said screen, the
faces of said control electrodes being on opposite
sides of the stream of cathode rays emerging from
the aperture in said anode and being substan-
tially parallel to said stream, means for apply-
ing anode potential between said anode and said
cathode, means for applying grid biasing poten-
tial between said grid electrode and said cathode,
and means integrally mounted in said tube for
transmitting without reflection from said screen
visible light directly from said fluorescent screen
to a point outside said tube.
